UNITED STATES PATENT OFFICE.

CHARLES A. BUCKLIN, OF NEW YORK, N. Y.

SYRINGE.

SPECIFICATION forming part of Letters Patent No. 659,130, dated October 2, 1900.

Application filed November 17, 1899. Serial No. 737,310. (No model.)

To all whom it may concern:

Be it known that I, CHARLES A. BUCKLIN, a citizen of the United States, and a resident of the city of New York, borough of Manhattan, in the county and State of New York, have invented a new and Improved Syringe, of which the following is a full, clear, and exact description.

This invention relates particularly to syringes for injecting medicine into the female organ; and the object is to provide a syringe of this character with a tapered enlargement at its outer end adapted to enter the mouth of the vagina forming a plug or stopper to prevent any outflow of liquid while the instrument is in use, and, further, to adapt the said enlargement for holding medicine to be used, the medicine being in tablets or otherwise.

I will describe a syringe embodying my invention and then point out the novel features in the appended claim.

Reference is to be had to the accompanying drawings, forming a part of this specification, in which similar characters of reference indicate corresponding parts in both views.

Figure 1 is a longitudinal section of a syringe embodying my invention, and Fig. 2 is a section on the line 2 2 of Fig. 1.

Referring to the drawings, 1 designates the barrel of the syringe, in which the piston 2 operates. At the outer end portion of the barrel is an enlargement 3, which is longitudinally tapered from the barrel outward, so that it may enter and tightly close the mouth of the vagina and effectually prevent the outflow of any injected liquid. This enlarged portion is made hollow, thus forming a con-

tainer for doses or tablets of medicine, and it is provided with a cover 4, which, conveniently, is made in the form of a flange on the gland 5, having a screw-thread engagement with the barrel of the syringe. The gland is cup-shaped and is made integral with the flange, so that both can be removed or applied together, and also by making the parts in one piece the cost to manufacture is very much reduced as compared to devices for the purpose made in separate parts. When the cover is removed, a tablet of medicine may be easily discharged from the container, and as the end of the barrel projects beyond the end of the container there will be no danger of a tablet falling into the barrel should the piston be wholly drawn out.

Having thus described my invention, I claim as new and desire to secure by Letters Patent—

A syringe, comprising a barrel, a hollow enlarged and longitudinally-tapered container at the upper end portion of the barrel and integral therewith, the end of the barrel being extended beyond the end of the container, a cup-shaped gland for the syringe-piston stem and adapted to engage with the barrel, and a flange on the gland serving as a cover for the container, the flange and gland being integral, substantially as specified.

In witness whereof I have signed my name to this specification in the presence of two subscribing witnesses.

CHARLES A. BUCKLIN.
